UNITED STATES PATENT OFFICE

MAX GARBELL, OF CHICAGO, ILLINOIS, ASSIGNOR TO VICTOR ADDING MACHINE COMPANY, OF CHICAGO, ILLINOIS, A CORPORATION OF ILLINOIS

TYPEWRITING MACHINE FRAME

Application filed December 14, 1927. Serial No. 239,821.

My invention relates to typewriting machines and it has particular relation to frame portions of such machines.

I will hereinafter more fully point out a method of producing a typewriting machine at a minimum cost of production. As one of the features contributing to this inexpensive structure I propose to utilize the hereinafter described frame member which comprises a minimum number of parts, each of which may be produced by a simple stamping or punching process. In fact I may, as I will hereinafter emphasize, form the principal part of the frame, that is a box-like structure having bottom and side walls, by drawing.

After having drawn the aforesaid box-like structure as the basis of my typewriting machine frame, I complete said structure by interfitting with said box-like member a number of transversely extending plates, which plates are adapted not only to complete the aforesaid frame structure and produce a closed key-board machine, but at the same time are intended, when in built-up form, to comprehend guideways for key-operated members forming part of my machine action. These members and the action of which they form a part are more particularly described and claimed in my copending application Serial No. 239,386, filed December 12, 1927.

The frame members utilized in constructing my invention and the hereinafter described method of assembling the same are particularly and definitely developed to coordinate with the action members of the machine so that said machines may be assembled very rapidly and cheaply, wherefrom the cost of producing the machines is reduced to a minimum. In this connection, as hereinafter emphasized, the aforesaid frame and transverse plate members are slotted to receive vertically extending portions of the key-operated members so that the placement of said members in operative position in the machine is a very simple proposition.

The advantages of the aforesaid frame and the method of assembling the same in connection with said key-operated members will

be better understood in connection with the accompanying drawings, in which

Figure 1 is an elevational, perspective view of a machine embodying my invention and assembled in accordance with the method hereinafter disclosed;

Fig. 2 is an elevational view of the frame member of the aforesaid machine stripped of nearly all the operating parts and partially in cross-section to disclose some of the essentials of my invention;

Fig. 3 is a perspective view, partially in cross-section, of some of the basic elements of my frame member; and,

Fig. 4 illustrates the transversely extending plate members which, by means of my invention, are interfitted with the base member shown in Fig. 3.

Referring to the drawings, a base or box-like member 10 is first formed by drawing or otherwise, it being my intention to so form and assemble the elements of my machine as to radically reduce the cost of production thereof. The said box-like portion of the structure 10 comprises a bottom 11, a rear wall 12, a front wall 13, and side walls 14 and 15. Extending transversely across the front portion of the structure 10 are strengthening elevated plates or girder-like members 11a and 11b, for purposes which I will hereinafter describe.

It will be observed that the said box-like structure comprehends the base member of a typewriting frame. A series of plates 16 to 20, inclusive, are next stamped, or otherwise suitably formed, to be interfitted with the structure 10 for forming a typewriting machine frame of the "closed" key-board type.

I will first describe these plates generally and thereafter point out that two of them are of special formation to fulfill particular purposes. Each of the plates is, in general, of Z-bar formation in cross-section, as best seen in Fig. 4; in fact these plates may be considered as bars extending between the side frames.

The lower arm of web 21 of said plates is, in the embodiment here shown (although the invention is not, of course, so limited), of double thickness. A leg or web 22 extends

vertically and an upper arm or web 23 completes the structure. Ears 24 are bent at right-angles to the lower web 21 and are utilized to secure these plates to the hereinbefore described box structure 10. The plates 17, 18, 19 and 20 are each provided with a series of slotted portions 25, it being observed that said portions are produced by slots struck inwardly from the fronts of the lower portions 21.

As hereinbefore indicated, the said lower portions of bars 17, 18, 19 and 20 are of double thickness, the upper thickness of said lower webs being designated as 21a and the lower thickness or layer as 21b, it being noted that the upper layers 23 of each of the bars are of such size that they are accurately received by and rest upon the thicknesses 21b which project forwardly and beyond the edges of the upper thicknesses 21a of the lower portions of the bars.

The lowermost plate or bar 16 may be properly termed the space-bar plate and is provided with but two slots 26, which slots are formed in recessed or depressed portions 27 of the lower web of the plate. Members 28 are formed complementary to the depressed portions 27 and are provided with slots 29 formed oppositely to the slots 26. I will describe the function of the complementary formation of the space-bar plate and securing members at a later point in this specification.

It is not deemed necessary to elaborate upon the formation of the top-most plate No. 20, since it will be seen that it is formed as the top plate of a typewriter frame having a vertical wall 22a curvilinearly formed at the rear thereof to comprehend a pleasing sweeping curve and to conceal the tops of any type bars, such as 30. Said top plate is also provided with the double thicknesses or layers 21a and 21b in its bottom web as heretofore indicated, and has ears 24 bent downwardly at either end thereof for securing purposes.

To understand more thoroughly the reason for my novel frame structure and the manner in which it may be expeditiously assembled in combination with the remaining elements of my key action reference may be had to Fig. 2 hereof and also to my copending application, Serial No. 239,336, filed December 12, 1927, in which said action is more fully described.

Said action comprises a series of key operated members 31. In some places I may refer to these members as levers, although they are in no sense pivoted, but rather move entirely rectilinearly and in a truly vertical direction. However, the industry and art have come to designate any and all members which carry a key struck by the finger as key levers, and it may, therefore, be necessary, in order to conform with the phraseology of the industry, to refer to these members as levers.

Said key members 31 comprise front vertical portions 32 and rear vertical portions 33.

It will be observed that the front portion 32 carries a key 34 on its upper end. Moreover, the slots 25 form guideways for said portion 32 and a complementary guideway 35 is formed in the plate 11a, which as heretofore described, extends transversely of the frame under the enclosing plate structure. Furthermore, a spring 36 is positioned between a lug 37 and the horizontally extending part of the key member comprehending one stop, and the plate 11a comprehending the other stop so that when said key 34 is depressed the spring 36 is stressed. Thereafter, when the finger pressure is relieved said key member is returned to normal position.

A further guide insuring true vertical motion of the key member is provided by slots 38 in a segment 39 in which segment the type bars 30 are pivotally mounted on a pivot wire 40. Said segment comprises the cross-piece 39 as shown, vertical legs 41 and horizontal portions 42; the segment being secured to the bottom 11 of the box structure by securing members 43 passing through said portions 42. The type bars 30 are provided with toothed gear portions 44 which are adapted to mesh with and be moved by teeth 45 on the upper and forward edge of the vertical extending portions 33 of the key members. The aforesaid geared or toothed connection is made within the slots 38 of the segment 39 and these slots, as intimated heretofore, form a guideway further to insure the accurate vertical movement of the key members 31 when the same are depressed.

Although not necessary for an understanding of this invention I deem it desirable further to indicate the universal bar structure of my machine. A universal bar 46 extends across the machine under the portions 31 of the key operated members and is adapted to be depressed thereby. The said bar 46 has arms 47 attached thereto which arms are pivotally mounted at 48-48. The bar furthermore comprehends a transverse member 49 at the rear ends of the arms 47-47 and a rearwardly extending lever bar 50, which bar is provided with a vertically extending member 51 surrounded by a returning spring 52.

When the bar or lever 46 is depressed by the portions 31, the rear end 51 is moved downwardly against the action of the spring 52 and, through certain connections more fully described in my copending application Serial No. 239,336, filed December 12, 1927, said universal bar serves to operate the ribbon vibrating mechanism, the ribbon feed mechanism and the escapement mechanism.

In Fig. 1, illustrating as it does a complete machine, further elements of the same are shown; for instance, a ribbon vibrator guide 53 is formed integrally with arms 54, which

arms are secured to the ends of the segment 39, thus comprehending a most desirable and inexpensive structure.

A platen 55 is supported in end frames 56—56 and is adapted to be spaced rotarily by a lever 57 which, with its associated mechanism, is more fully described in my copending application, Serial No. 236,920, filed December 1, 1927. The end frames 56 are mounted on the upper rail 57 of a carriage rail assembly embodying a lower rail 58 with separating members therebetween, these latter and the carriage rail assembly being more fully described in my copending application, Serial No. 191,650, filed May 16, 1927.

Having described the essential elements of my machine, and a complete operative reduction thereof, I will now indicate the way in which the same is assembled in a novel and efficient manner at a low cost.

After the box structure 10 has been prepared, as shown in Fig. 3, the upper bank of key operated members is placed in position (although I do not confine myself to this method of assembly, the gist of the invention being in making the plates and base in the form indicated and thereafter simultaneously building up a closed front machine and at the same time supporting the key operated members for proper operation).

The top plate 20 is associated with said upper bank key members and will support and enclose the vertical extending front portions 32 of said key operated members as shown. The next lower plate is then secured in position to close the front of the slots, it being observed that at this time the portion 23 fits flush over the protruding portion 21b, which will not only close the slots but will eventuate a smooth flush surface for each successive step of the frame.

In like manner each of the banks of the key operated members is positioned, and finally the space bar is placed in position. In the latter case, after the bar has been entered through the slots 26, the securing members 28 are placed in position and again a smooth step or plate is produced as shown in Fig. 1.

This method of assembly of my improved frame portion is of marked advantage in reducing the cost of the machine, and so far as strength and beauty are concerned in no way suffers by comparison with the more elaborate machines wherein the action of necessity requires considerable more time in positioning. Moreover, the enclosed key board is of considerable advantage, not only in preventing tampering with the delicate parts of the machine, but in excluding dust or other débris from the operating portions and the guide ways.

While I have described but one embodiment of my invention and the method of assembling the elements thereof, I wish it understood that considerable modification may be

indulged in, by those skilled in the art, without departing from the spirit of my invention, and I desire, therefore, that my invention be limited only by the prior art and the appended claims.

I claim:

1. In a typewriting machine embodying key operated members, a frame therefor comprising a box member having a bottom and walls rising therefrom and plates disposable on said walls for building up an enclosed frame for said machine, the front portion of the side walls of said box being stepped and said plates being shaped to interfit with said stepped walls to comprehend a stepped casing front for the several key banks, one of said plates being placeable at the lowermost step, and a space bar accommodated thereby, said lowermost plate being slotted to receive portions of said bar, and securing members associative with said latter plate to produce a flush surface structure.

2. In a typewriting machine embodying key operated members, a frame therefor comprising a box member having a bottom and walls rising therefrom and plates disposable on said walls for building up an enclosed frame for said machine, the front portion of the side walls of said box being stepped and said plates being shaped to interfit with said stepped walls to comprehend a stepped casing front for the several key banks, each of said plates being of Z-bar structure in cross-section with the lower portion thereof slotted and the upper portion of said plates adapted to interfit with the lower portion of the next higher plate.

3. In a typewriting machine embodying key operated members, a frame therefor comprising a box member having a bottom and walls rising therefrom and plates disposable on said walls for building up an enclosed frame for said machine, the front portion of the side walls of said box being stepped and said plates being shaped to interfit with said stepped walls to comprehend a stepped casing front for the several key banks, each of said plates being of Z-bar structure in cross-section, with the upper portion of each plate adapted to interfit with the lower portion of the next higher plate.

4. In a typewriting machine embodying key operated members, a frame therefor comprising a box member having a bottom and end walls rising therefrom and plates disposable on said walls for building up an enclosed frame for said machine, the front portion of the side walls of said box being stepped and said plates being shaped to interfit with said stepped walls to comprehend a stepped casing front for the several key banks, each of said plates being of Z-bar structure in cross-section, the upper portion of said bar adapted to interfit with the lower portion of the next higher plate, and each of said plates having

ears at the ends thereof to permit of securing to said side walls.

5. In a typewriting machine embodying key operated members, a frame therefor comprising a box member having a bottom and end walls rising therefrom and plates disposable on said walls for building up an enclosed frame for said machine, the front portion of the side walls of said box being stepped and said plates being shaped to interfit with said stepped walls to comprehend a stepped casing front for the several key banks, each of said plates being of Z-bar structure in cross-section, the upper portion thereof being adapted to interfit with the lower portion of the next higher plate, each of said plates having ears at the end thereof to permit of securing to said side walls and said side wall portions being recessed complementary to said ears to eventuate a flush side wall when said frame assembly is completed.

6. In a typewriting machine embodying key operated members, a frame therefor comprising a box member having a bottom and walls rising therefrom and plates disposable on said walls for building up an enclosed frame for said machine, the front portion of the side walls of said box being stepped and said plates being shaped to interfit with said stepped walls to comprehend a stepped casing front for the several key banks, each of said plates being of Z-bar structure in cross-section with the lower portion thereof slotted and the upper portion thereof being adapted to interfit with the lower portion of the next higher plate, and said lower portions being of plural thickness with the bottom thickness extending forwardly to provide a rest for said upper portion when the latter is interfitted with the plate next above.

7. In a typewriting machine embodying key operated members, a frame therefor comprising a box member having a bottom and walls rising therefrom and plates disposable on said walls for building up an enclosed frame for said machine, the front portion of the side walls of said box being stepped and said plates being shaped to interfit with said stepped walls to comprehend a stepped casing front for the several key banks, and a guide plate extending transversely of said machine and under said stepped plates and adapted to receive portions of said key operated members.

8. In a typewriting machine embodying key operated members, a frame therefor comprising a box member having a bottom and walls rising therefrom and plates disposable on said walls for building up an enclosed frame for said machine, the front portion of the side walls of said box being stepped and said plates being shaped to interfit with said stepped walls to comprehend a stepped casing front for the several key banks, and a

guide plate extending transversely of said machine and under said stepped plates and slotted under each of the slots in said stepped plates to receive vertically moving portions of said key operated members.

9. In a typewriting machine embodying key operated members, a frame therefor comprising a box member having a bottom and walls rising therefrom and plates disposable on said walls for building up an enclosed frame for said machine, the front portion of the side walls of said box being stepped and said plates being shaped to interfit with said stepped walls to comprehend a stepped casing front for the several key banks, each of said plates being of Z-bar structure in cross-section with the lower portion thereof slotted and the upper portion adapted to interfit with the lower portion of the next higher plate, the upper portion of the top-most plate of said series, including, in addition to said slots, a properly shaped top plate conformation.

In witness whereof, I have hereunto subscribed my name.

MAX GARBELL
